UNITED STATES PATENT OFFICE

CONRAD ROSINE, OF CHICAGO, ILLINOIS

DESIGN FOR A COMBINED CIGARETTE DISPENSER AND MATCH-BOX HOLDER

Application filed May 28, 1930. Serial No. 35,800. Term of patent 7 years.

To all whom it may concern:

Be it known that I, CONRAD ROSINE, a citizen of the United States, residing at Chicago, in the county of Cook and State of Illinois, have invented a new, original, and ornamental Design for a Combined Cigarette Dispenser and Match-Box Holder, of which the following is a specification, reference being had to the accompanying drawing, forming part thereof.

In said drawing:

Figure 1 is a perspective view of a combined cigarette dispenser and match box holder showing my new design looking at the front and one end of the article; and

Fig. 2 is a perspective view thereof looking at the same end and at the back of the article.

I claim:

The ornamental design for a combined cigarette dispenser and match box holder, as shown.

CONRAD ROSINE.
